UNITED STATES PATENT OFFICE

FREDERICK C. SCHOLLER, OF PHILADELPHIA, PENNSYLVANIA

THREAD OILER OR MOISTENER

Application filed February 20, 1926. Serial No. 89,529.

My invention relates to what are ordinarily termed "oilers" for yarns or threads by which they are oiled, or wet, or otherwise treated by a liquid during the passage 5 through the device.

The main purpose of my invention is to equalize the amount of treating liquid taken up by different parts of the fiber.

A further purpose is to submerge the yarn, 10 or other fiber, in the liquid and yet to render the time of treatment wholly independent of the depth of liquid in the device.

A further purpose is to submerge the fiber in the treating liquid by a float whereby the 15 extent of submersion will be maintained uniform by the uniformity of the position of the float with respect to the surface of the liquid.

A further purpose is to simplify the construction of the oiler as well as facilitate 20 placing and replacing the fibers in the device.

A further purpose is to provide a wiper for the thread or fiber as it comes from the oiler.

A further purpose is to provide a drag 25 for the fiber to prevent overrunning of the fiber when it is drawn at a non-uniform rate.

A further purpose is to reduce the splashing from an oiler or moistener.

Further purposes will appear in the specification and in the claims.

I have preferred to illustrate my invention by one main form only, with slight modifications, selecting a form which is practical, efficient, simple and inexpensive, and which at the same time well illustrates the principles of my invention.

Figure 1 is a top plan view of one construction of my invention, omitting certain 40 parts which may be used with it.

Figure 2 is a section of Figure 1 taken upon line 2—2.

Figure 3 is a perspective of the float in Figures 1 and 2.

45 Figures 4, 5 and 6 are sections corresponding generally to Figure 2 showing slightly modified forms.

Figure 7 is a perspective of the float seen in Figure 4.

50 Figure 8 is a top plan view of another em-

bodiment of my invention, carrying a wiper and drag.

Figure 9 is a side elevation of the structure of Figure 8.

Figure 10 is a section upon line 10—10 of 55 Figure 8.

Figure 10^a is a fragmentary section of a modification of Figure 10.

In the drawings similar numerals indicate like parts.

For convenience in manufacture, ease of cleaning, freedom of access and clearness of view as to height of liquid, I prefer to make the vessel 5 of glass.

The length of the container will depend 65 largely upon the number of fibers which are to be oiled in the container. In the present case I have provided for two well spaced fibers.

Within the container I provide a float 6 70 which is intended to depress the fibers 7 to a uniform extent beneath the surface of the liquid 8. So far as my invention is concerned it is immaterial whether the fibers are depressed by passing beneath the body 75 of the float as in Figures 1, 2, 3 and 6 or passed through an opening in the body beneath the liquid surface as in Figure 4, or passed through guides carried by the float and hence maintained by it at uniform depth 80 beneath the liquid surface as in Figure 5. My invention in its broader aspects is independent also of the character of guiding means employed and of whether there be any guide carried by the float or by the container 85 5. The guiding function can be performed by wholly external guides, as in Figure 6.

The structure in Figures 1 and 2 utilizes a long float 6, having guiding grooves 9 through which the fiber passes and by which the fibers are separated within the liquid. The use of a round float in this figure reduces friction upon the fibers by permitting the float to turn. Side and end play are prevented while providing an enlarged reservoir for the oil, or other treating liquid, by the use of ribs 10 and 11. Grooves 12 at the top perform a guiding function there.

In the form shown in Figure 4 the float 6' is apertured at 13 to provide openings 100

through which the fibers pass and are guided. It performs the same functions as in the form in Figures 1-3, except that the float cannot rotate.

5 In the form shown in Figure 5 the float carries guides 14 by which the fiber is depressed beneath the liquid and guided in its passage through the liquid. These guides may be made of wire tightly fitting the float to retain the guides in position by their grip upon it. Where the float is free from danger of rotation, as in this form, these guides need not be completely closed at the bottom but are nevertheless preferably in the form of spirals, loose enough for the thread to be passed into them freely in the spaces between the turns and without necessity for threading through the apertures.

20 In the form shown in Figure 6 the guiding function is intended to be performed primarily by outside guides 12' of any suitable character, wholly separate from or forming part of, or mounted upon other mechanism. Here the guides may also be of spirals loose enough to permit side insertion of the fiber. A plain stick float 6² is used.

Separate guides are not so satisfactory as guides forming part of the device as in the other forms.

30 In the form shown in Figures 8, 9 and 10 a float 6³ is shown intended to oil a single fiber only. It is grooved at 9' and its ends 15 fit within the grooves 16 in the side walls of a perfectly plain vessel 5'. In conjunction with this form I have shown a drag and wiper equally desirable in connection with any of the other forms and which can be applied to any vessel. There is no reason why it can not be made integral with the vessel and I have shown the drag and wiper as separable from it for the reason only that I prefer this separability in order that the drag and wiper can be cleaned effectively with less trouble.

45 In the means of attachment shown, equally suitable for the other vessel illustrated, the combined drag and wiper 17 is provided with a bracket 18 in the form of ears 19 which straddle the wall 20 and bear on opposite sides of it. If applied in single form to vessels of the character of that shown in Figure 1, it would be applied to such parts as 20' of the wall of this vessel.

55 With any machine having intermittent feed, such as a full-fashioned hosiery machine, it is desirable to prevent overcasting of the thread. I do this by putting a drag upon the thread by guiding it through a tortuous passage here provided by staggered pins 21. At the same time I provide for drainage of these pins in order that they may perform a wiping function to the best advantage. I provide also an additional wiper in the form of ribs 22, preferably diagonal to the general path of the thread so

that, with the slope of the base 23 upon which they are mounted, there will be free drainage through the spaces between the ribs for any excessive oil or other liquid which the fiber may have carried from the pool of liquid.

70 By this construction, the means for stopping the overcast is made to still further equalize the oiling or wetting of the fiber, as any undue amount of oil or other liquid taken up by the fiber during an interim in the feed will be removed from it during the progress of the fiber through the wiper.

75 The combined drag and wiper is effective to substantially eliminate splashing as vibration of the thread is greatly reduced and the excess of liquid normally splashed is taken up by the wiping action.

80 My drag is adjustable since, by omitting one or more of the turns of the tortuous path (i. e., skipping one or more pins) the amount of drag is lessened. It can thus be adapted to the needs of the particular fiber handled.

85 My drag and wiper is the most desirable construction for this purpose known to me. I appreciate however, that with somewhat less advantage a drag and wiper of fiber material such as felt, possessing capillary attraction, could be used, separately or that it could be used to assist in the action, placing it on a drain-board and passing the thread over or under it. Such a construction is shown in Figure 10^a, where the felt pad 24 rests upon the drain-board and receives oil or other liquid from the thread 7. This pad 24 is shown as located partly at 24' about the pins and between the ribs (which thus hold it in place) and partly at 24² beyond the last rib. It may occupy either or both positions. It can of course be placed ahead of the drag shown in Figure 10, as at 24³, and can be used without the ribs or pins or without either of them as desired.

90 It will be evident that the uniformity in the depth of submersion of the fiber, the draining drag upon the fiber as it leaves the liquid and the draining wiper all combine to equalize the extent of oiling or wetting of the fiber.

95 It will be further evident that the arched relation of the wiping ribs insures contact of each of the ribs with the fiber to wipe it and that the diagonal position of the ribs and the general slope of the support insure drainage, not only for the ribs themselves but for the pins used as guides and wipers and providing the tortuous passage.

100 In operation the fiber need only be passed beneath the float, in most of the forms, to find its own guided position in line with the guides in the walls of the vessel or separate guides upon or independent of the vessel.

105 The drag ensures that the speed of passage of the thread or fiber through the liquid shall

be that of the mechanism drawing it, thus giving uniform extent and time of immersion during feeding operations.

Such tendency to splash as is due to whipping of the thread where the feed is intermittent is taken care of by the drag.

The proper performance of the wiping function involves some drag. I have aimed to provide for additional and adjustable drag where this is desired with a variety of wiping means capable of independent or combined use. The wiper takes up and drains away from the thread any excess of oil or liquid carried over, preventing splashing and making uniform the oil or liquid content of the thread or fiber.

Replacements of threads involve a minimum of time and trouble and so long as the bottom of the float is above the bottom of the vessel the extent of immersion of the fiber is uniform.

In view of my invention and disclosure variations and modifications to meet individual whim or particular need will doubtless be come evident to others skilled in the art, to obtain part or all of the benefits of my invention without copying the structure shown, and I, therefore, claim all such in so far as they fall within the reasonable spirit and scope of my invention.

Having thus described my invention what I claim as new and desire to secure by Letters Patent is:—

1. In a liquid treating device for textile purposes, a container adapted to hold the treating liquid and a freely floating grooved roller guide adapted to float in the liquid and to submerge a thread beneath the liquid in combination with guide means for limiting the bodily movement of the float.

2. In a liquid treating device for textile threads, a vessel adapted to hold a liquid, a float of approximately circular section in the vessel grooved and adapted to guide a thread therein beneath the surface of the liquid and guides within the vessel adapted to restrain the float from lateral movement.

3. In a liquid treating device for textile threads, a vessel adapted to hold a liquid, means for guiding the thread to pass beneath the surface of the liquid and a drag for the thread as it passes from the liquid providing a tortuous passage for the thread and adapted to wipe the fiber.

4. In a liquid treating device for textile threads, a container adapted to hold the treating liquid, a grooved single piece float therein directing the fiber to be treated through the groove of the float and guides for limiting the lateral movement of the float while permitting it to float freely.

5. In a liquid treating device for textile threads, a vessel adapted to hold a liquid, having ribs therein confining the open spaces to smaller dimensions than the maximum in-

terior dimensions of the vessel and a float fitting between the ribs, laterally guided by them and adapted to be sustained by the liquid over a wide range of depth of the liquid.

6. In a liquid treating device for textile threads, a vessel adapted to hold a liquid, means for guiding the thread to pass beneath the surface of the liquid and a drag for the thread comprising staggered guides for the thread adapted to wipe excess liquid from the thread and drain the excess liquid free from the thread.

7. In a liquid treating device for textile threads, a vessel adapted to hold a treating liquid, means for guiding a thread beneath the surface of the liquid and a wiper for the thread comprising ribs and drainage spaces whereby the liquid wiped from the thread is drained from the ribs.

8. In a liquid treating device for textile threads, a vessel adapted to hold a treating liquid, means for guiding a thread beneath the surface of the liquid and a wiper for the thread comprising guides forming a tortuous passage for the thread and ribs over which the fiber is passed, both adapted to wipe the thread and drain liquid from it.

9. In a liquid treating device for textile threads, a vessel adapted to hold a treating liquid, a float in the vessel, adapted to guide the thread to a uniform distance beneath the surface of the liquid and a combined drag and draining wiper engaged by the thread as it leaves the liquid.

10. In a liquid treating device for textile threads, a vessel adapted to hold a treating liquid, a float in the vessel, adapted to guide the thread to a uniform distance beneath the surface of the liquid and a combined tortuous passage drag and wiper through which the thread passes as it leaves the liquid.
